United States Patent Office

Des. 178,460
Patented Aug. 7, 1956

178,460

PUFFED TEXTILE FABRIC

Douglas D. McCord, New York, N. Y., assignor to Chicopee Mills, Inc., a corporation of New York

Application June 7, 1955, Serial No. 36,415

Term of patent 14 years

(Cl. D92—1)

FIG. 1

Fig. 1 is a plan view of a puffed textile fabric showing my new design; and Fig. 2 is an edge view of Fig. 1.

I claim:

The ornamental design for a puffed textile fabric, as shown.
